UNITED STATES PATENT OFFICE.

JAMES T. BAKER, OF BUSTLETON, PENNSYLVANIA.

BOTTLE-CLOSURE.

1,170,393.

Specification of Letters Patent.

Patented Feb. 1, 1916.

Application filed April 3, 1914. Serial No. 829,322.

To all whom it may concern:

Be it known that I, JAMES T. BAKER, a citizen of the United States, residing at Bustleton, in the county of Philadelphia and State of Pennsylvania, have invented new and useful Improvements in Bottle-Closures, of which the following is a specification.

The invention relates to closures for bottles and more particularly to closures for use on milk bottles or the like, in which it is desired to provide a closure which will keep the contents of the bottle clean and sanitary and in which the closure itself will be of a clean, sanitary and neat appearance.

15 The invention embodies, among other features, the provision of a closure which will not only close the opening of the bottle but which will also cover and completely inclose the upper part of the neck of the bottle and 20 over which the milk or other fluid is usually poured when the bottle is tilted after removing the cover therefrom, thus preventing foreign matter or germs from accumulating on that portion of the bottle over 25 which the fluid is adapted to be poured.

30 The invention still further embodies the provision of a simple and effective closure that can be cheaply manufactured and which will prevent foreign matter or germs from 35 passing around its edge and entering the neck of the bottle.

In the further disclosure of the invention reference is to be had to the accompanying drawings, constituting a part of this specification, in which similar characters of reference denote corresponding parts in all the views, and in which:

Figure 1 is a plan view of the bottle showing the closure applied thereto, parts being 40 broken away to disclose the underlying structure; Fig. 2 is a fragmentary side elevation of the upper portion of the bottle, showing the device applied thereto, with parts broken away to disclose the underlying 45 structure and the closure shown in section; Fig. 3 is a bottom plan view of the closure; and Fig. 4 is a fragmentary elevation of a modified form of my device.

Referring more particularly to the views, 50 I disclose a bottle 1 having the usual neck 2 provided with an opening or mouth 3, the said bottle having small tapered sides 4.

The bottle, after being filled, is provided with a top or closure and which consists, more particularly, of a flat disk-like portion 5 terminating in a depending outwardly diverging annular flange 6, the parts 5 and 6 being preferably made of paper, papier mâché or any other suitable material which will be of a clean and sanitary nature. The 60 sides forming the rim or flange 6 are tapered very slightly so that after the device is pressed into position on the bottle, as shown, a positive frictional engagement exists to hold the closure against accidental 65 displacement.

The closure shown can be conveniently adapted for use as an advertising medium in that it provides sufficient space for printing an advertisement thereon either upon the 70 flat disk-like portion 5 or the rim 6.

In Fig. 4 I disclose a modified form of the device and in which the annular rim 6 is crimped to provide a series of corrugations 7 which tend to contract the rim against the 75 side of the bottle neck and beneath the usual bulged portion 8 of the bottle, thus more firmly holding the closure in place.

Having thus described my invention, I 80 claim:

A device of the class described, a closure for bottles comprising single piece of paper formed to provide a smooth flat disk-like top, and a smooth depending annular rim, with the top adapted to fit tightly 85 against the entire top edge of the bottom and the rim snugly encircling the adjacent neck portion thereof and frictionally engaging the neck, and a series of relatively spaced corrugations formed on the smooth depending annular rim at the lower edge thereof by gripping the same, with the rim depending inwardly at substantially its medial portion and at the points of formation of the corrugation whereby said corrugation will 95 bear tightly against the outer face of the neck.

In testimony whereof I affix my signature in presence of two witnesses.

JAMES T. BAKER.
